(57) **CLAIM**

The ornamental design for furniture, as shown and described.

DESCRIPTION

FIG. 1 is a perspective view of furniture showing our new design;

FIG. 2 is a front view thereof;

FIG. 3 is a rear view thereof;

FIG. 4 is a right side view thereof, the left side view being a mirror image;

FIG. 5 is a top view thereof; and,

FIG. 6 is a perspective view of a second embodiment showing our new design, which differs from the first embodiment only in that the handles of the second embodiment are stippled to reflect a contrasting color to the rest of the design.

The broken lines in FIGS. 1-7 are shown for environmental purposes only and form no part of the claimed design.
